UNITED STATES PATENT OFFICE.

WILLIAM F. BROWN, OF NEWARK, NEW JERSEY, ASSIGNOR TO THE BIGELOW CARPET COMPANY, OF SAME PLACE.

DESIGN FOR A CARPET.

SPECIFICATION forming part of Design No. 23,261, dated May 15, 1894.

Application filed April 19, 1894. Serial No. 508,217. Term of patent 3½ years.

To all whom it may concern:

Be it known that I, WILLIAM F. BROWN, a subject of the Queen of Great Britain, residing at Newark, in the county of Essex and State of New Jersey, United States of America, have invented and produced a new and original Design for a Carpet, of which the following is a full, clear, and exact description, reference being had to the accompanying drawing, forming a part thereof, which represents a face view of the carpet in which the new design is embodied.

The invention relates to a design to be worked into or upon surfaces such as carpets or similar fabrics, and it consists in the novel configuration of figures as herein shown and claimed.

The design consists of a body A and border B. The body A is decorated with flowers of the cultivated rose variety, together with foliage arranged in festoon order, the festoons appearing connected by ribbons, and the festoons are represented as encircling groups of

roses of the wild variety, the groups being separated by fanciful figures. The border B is decorated with a fan figure ornamented with roses, together with festoons of roses of the cultivated variety connected by ribbons, and between the fan figures and festoons the representation of a group of flowers is produced, the flowers being of the type of the wild rose. The border is further ornamented by an ornamental dado at its outer edge and an ornamental scroll at its inner edge.

I claim—

1. In a design for a carpet, the body A, substantially as shown.
2. In a design for a carpet, the border B, substantially as shown.
3. The design for carpets, consisting of the body A and border B, substantially as shown.

WILLIAM F. BROWN.
